UNITED STATES PATENT OFFICE.

IRA L. CAIN, OF SAN ANGELO, TEXAS.

ELECTRICALLY-OPERATED DOOR.

1,192,856.

Specification of Letters Patent. Patented Aug. 1, 1916.

Application filed May 5, 1915. Serial No. 26,122.

To all whom it may concern:

Be it known that I, IRA L. CAIN, a citizen of the United States, residing at San Angelo, in the county of Tom Green and State of 5 Texas, have invented new and useful Improvements in Electrically-Operated Doors, of which the following is a specification.

My invention relates to improvements in entrance doors for buildings and more 10 especially with reference to improvements in electrically operated means for opening and closing the double doors of office and other like buildings, the object of the invention being to provide improved means of this character by which a door is opened as a person 15 approaching the door steps on a manually operable circuit closer and is closed as the person after passing the door steps on another manually operable circuit closer, so 20 that the mechanism performs all the functions of opening and closing the door, without the services of an attendant and without effort on the part of the person using the door.

With the above and other objects in view 25 the invention consists in the construction, combination and arrangement of devices hereinafter described and claimed.

In the accompanying drawings:—Figure 30 1 is a diagrammatic plan of a pair of sliding doors provided with electrically actuated means for opening and closing them, constructed and arranged in accordance with my invention. Fig. 2 is a diagrammatic elevation of one of the doors and its opening 35 mechanism, and showing the door in closed position. Fig. 3 is a similar view, from the reverse side, showing the door in open position and showing its releasing mechanism. Fig. 4 is a detail elevation of the door carried 40 tappet, the electromagnet, the switch and the make and break devices of the motor and electromagnet circuits which are alternately and reversely operated by the switch.

For the purposes of this specification a 45 pair of sliding doors 1 are indicated in Fig. 1 of the drawings. Each of these doors is provided with electrically actuated means for opening the door, releasing it after being 50 opened, and for then automatically closing it and since such operating means is identical for each of the doors I only describe the operating means for one of the doors herein it being understood that the operating means 55 for the doors are reversed as indicated in Fig. 1 and arranged so that a person on

entering the building provided with the doors will enter by the right hand door and when leaving the building will use the other door.

Each door 1 is slidably mounted and is here shown as provided with suspended hangers 2 at its upper side, said hangers having rollers 3 which engage an elevated track rail 4. A weight 5 is here shown for closing 60 each door, said weight being connected to the door by a cord 6 which passes over a direction pulley 7. Each door is provided at its lower side and near its outer edge with a wedge-shaped tappet cam 8.

On one side of each door and in the way of a person approaching said door to use it when entering the building I provide a foot plate 9, which is arranged in the floor, is vertically movable, is depressed when 70 stepped upon, and is provided with springs 10 for raising said plate after the person has stepped off the same.

To open the door I provide an electric 80 motor indicated at 11 and the shaft of which is provided with a suitable drum 12 for winding and unwinding a cord 13 which is attached to the door as at 14 and engages a direction pulley 15. The motor is included in an electric circuit 16 which also includes 85 conductors 16^a, a source of electric energy here indicated as a battery 17, a normally open circuit closer 18, which is operated by the plate 9 when the latter is depressed and contacts 18^a.

On the opposite side of the door from the plate 9 is a similar plate 19 which is adapted to be stepped upon by a person who has used and passed the door in entering, this plate 19 having springs 20 to normally hold 90 the same in raised position. An electromagnet 21 is included in a normally open circuit 22 with a circuit closer 23 operated by depressing the plate 19, the battery or source of electricity 17 and contacts 24. 100 Said circuit 22 also includes the conductors 16^a as indicated in Fig. 1. A spring switch arm 25 is arranged between the contacts 18, 24 to alternately cause them to close the motor circuit 16 and the electromagnet circuit 105 22. This spring switch arm has a cam-shaped free end 26 provided with a shoulder 27 and is also provided, on its lower side, with an armature 28, attracted by the electromagnet. When the door is closed by the 110 action of its weight 5 the cam tappet 8 is away from the cam end of the switch, the

motor circuit is opened at 18 and is closed at 18^a. When a person approaches the door from the outside, to enter through it, he steps upon the plate 9, thereby closing the 5 motor circuit at 18 and hence puts the motor in operation and causes the drum 12 to partly wind the cord 13 and thereby move the door to open position and raise the weight 5 attached to the door. As the door reaches a nearly fully opened position its cam 8 depresses the cam end 26 of the switch 25 causing said switch to open the motor circuit at 18^a and to close the electromagnet circuit at 24. As the person after passing 15 the door reaches the plate 19 he steps upon said plate and depresses it, thereby causing the said plate to close the electromagnet circuit at 23 so that the electromagnet becomes energized and attracts the armature 28, and by so doing releases the shoulder 27 of the switch cam from the cam 8, thus releasing the door, which is thereupon closed by its weight 5 and as the person steps from the plate 19 the electromagnet circuit is reopened at 23, the motor circuit is closed again at 18^a and the electromagnet circuit is opened at 24, thus restoring all the parts to initial position.

Having thus described my invention I 30 claim:

1. An electric circuit including a source of electricity, a motor, contacts, and a normally open circuit closer; a second circuit including said source of electricity contacts,

an electromagnet, and a second normally 35 open circuit closer; a door arranged for operation by the motor and having a tappet, and a switch arm operable by the tappet to open the first named contacts when the door reaches open position and to engage the tappet and thereby lock the door in such position, and to also close said second named contacts, and having an armature for attraction by the electromagnet, to release the switch from the tappet and permit the door 40 to close.

2. An electric circuit including a source of electricity, a motor, contacts, and a normally open circuit closer; a second circuit including said source of electricity, contacts, 50 an electromagnet, a door opened by the motor, and having a tappet, means to close the door when the motor is out of operation, and a switch arm operable by the tappet, to open the first named contacts when the door reaches open position, and to engage the tappet and thereby lock the door in such position, and to also close said second contacts, and having an armature for attraction by the electro-magnet to release the switch 55 from the tappet, and permit the door to close.

In testimony whereof I affix my signature in presence of two witnesses.

IR A L. CAIN.
